UNITED STATES PATENT OFFICE

2,426,866

ELECTRON OPTICAL SYSTEM

Dennis Gabor, Rugby, England, assignor to General Electric Company, a corporation of New York

Application February 12, 1944, Serial No. 522,138
In Great Britain March 3, 1943

9 Claims. (Cl. 250—161)

1

This invention relates to electron optical systems and, more particularly, to systems of this type employed in electron microscopes. It has for its object to provide an improved electron lens arrangement for such a system.

In the field of electron microscopes, it is known that spherical aberration of the electron lenses used constitutes a limiting factor in the resolution power of such microscopes. Efforts to correct spherical aberration of such lenses have proved fruitless, primarily since there exists no electron-optical equivalent of the dispersing lens or of the correcting plates used in light optics for the elimination of this defect. Due to the inability to correct for spherical aberration, prior to this it has been impossible to make the resolution limit of electron microscopes less than about 30 Angstroms. This limitation is partly due to the impossibility of correcting for spherical aberration which makes it necessary to use extremely small apertures; and partly also to the practical impossibility of constructing objective lenses having focal lengths less than about 3 millimeters. When electron lenses having focal lengths of this order are employed, the fluctuations of the energizing voltage, even if these fluctuations are made as small as .002%, by defocusing of the lens produce errors of nearly the same size as those produced by spherical aberration and diffraction. Further progress in decreasing the resolution limit of electron microscopes, therefore, depends upon the correction of spherical aberration and substantial reduction in the focal lengths of the objective lenses. Accordingly, it is an object of the present invention to provide an electron lens having an extremely short focal length.

Another object of the invention is to provide an improved electron lens system in which the spherical aberration of the lenses is substantially reduced.

Still another object of the invention is to provide a space charge lens for an electron optical system.

A still further object of the invention is to provide an improved electron lens for an electron optical system in which the electrons of an electron stream passing through the lens are focused to a path substantially parallel with the axis of the stream.

One of the features of the invention consists in the improvement of a condensing lens which may be of either the magnetic or electrostatic type by combining therewith a dispersing lens which, in conjunction with an auxiliary cathode,

2

produces a concentrated cloud of slow electrons along a portion of the optical axis and trapping the cloud of electrons within a closed space by the combined effect of electrostatic and magnetic fields.

5 Electrode means are provided to remove electrons from the cloud at the rate they are supplied by the auxiliary cathode to maintain a desired density of the concentrated electron cloud.

10 The features of the invention which are believed to be novel are set forth with particularity in the appended claims. The invention itself, however, both as to its organization and method of operation, together with further objects and 15 advantages thereof, may best be understood by reference to the following description taken in connection with the accompanying drawing, in which Fig. 1 is a part section through an electron lens system according to the invention; Figs. 2 and 3 are diagrams illustrating the manner in 20 which a short resulting focal length is produced by the lens system; and Fig. 4 illustrates the distribution of the space charge density and potential in the region of the concentrated electron cloud.

In the part section of the objective lens of the invention illustrated in Fig. 1, there is schematically represented only the upper half of the electron lens system, the lower half being identical

30 thereto. The objective lens as depicted comprises a coil or winding 1 enclosed in a magnetic metallic casing 2 to constitute a magnetic lens of well-known type. A stream of high-speed image-bearing electrons represented by the arrow

35 3 passes along the axis 4 of the coil 1. A second lens, arranged axially behind the magnetic lens, comprises a coil or winding 5 enclosed in a metallic magnetic casing 6 and concentrically surrounding a tubular electrode 7.

An auxiliary 40 cathode 8, in the shape of an annular filament, is disposed near the entrance to the second lens system and is supplied with heating current by means of leads 9 energized from a suitable source of potential. Electrode 7 is maintained at a positive potential with respect to cathode 8 by means of lead 10 connected to a suitable source of potential.

The electron lens arrangement illustrated in Fig. 1 may be employed in an electron microscope, 50 the remaining portions of which may be of any well-known form and are not illustrated. In the usual non-self-luminous type of electron microscope, the image is formed by electrons, produced by a separate cathode, which strikes the object under examination after having been accelerated

to a rather high velocity. Thereafter, the electron beam 3 is subjected to the effects of the lens system and ultimately is directed to either a fluorescent screen or a photographic film.

In a condensing lens of the magnetic type, such as the coil 1 in Fig. 1, the magnetic field exerts a force at right angles to the path of the electrons of the beam 3 in the field, producing a sort of spiral path for the electrons. This motion can be separated into movement in a meridian plane and rotation around the axis. A magnetic field of this type is always a condensing lens and the trajectory of the electrons is always bent toward the axis.

The action of the second lens in Fig. 1 comprising the coil 5 and the tubular electrode 7 is essentially different from that of the first lens. In this second lens, the magnetic coil 5 produces a long, but weaker, field along the axis of the electron beam 3 than the coil 1. The two magnetic fields have the same sign but there is a leakage region between the two in which the field strength goes to zero. This field line of zero strength has approximately hyperbolic shape and is indicated in Fig. 1 by the line 11. In some instances it may be necessary, in order to produce this zero region, to use a special coil between the two windings 1 and 5. The auxiliary cathode 8 is located on this line of zero field strength and serves as the electron source for a cloud of low-speed electrons present within the tubular electrode 7, the latter being maintained at a positive potential with respect to cathode 8.

It is known that an electron emitted from a cathode and moving in an axially symmetrical magnetic field acquires an angular momentum relative to the axis. The value of this angular momentum is proportional to the number of lines of magnetic force which intersect the surface of revolution generated by rotating the trajectory of the electron around the axis. Hence, an electron of the beam 3 which has crossed a certain magnetic flux on its way from the main cathode (not shown) can never reach the axis 4, as at the axis its angular momentum would be zero. In order, therefore, to let electrons reach the axis at all, it is necessary to arrange at least part of the auxiliary cathode 8 in such a position that the flux between this cathode and the axis is zero. This is achieved in the structure of Fig. 1 by placing the cathode 8 at or near the surface of revolution 11 at which the magnetic intensity is zero.

If the magnetic field set up by the coil 5 is of sufficient strength, the electrons of the cloud within the second lens system are never able to reach the sheath electrode 7 which has a potential positive with respect to cathode 8. As an electron moves outwards, its angular momentum increases, that is, its kinetic energy is converted partly into rotational energy. If the magnetic field produced by the coil 5 is of sufficient strength relative to the voltage difference between cathode 8 and sheath 7, at a certain radius, indicated by the dotted line 12, the whole movement of the electrons from cathode 8 becomes rotational, that is, at right angles to the plane of the drawing in Fig. 1. Under such conditions, the electrons cannot approach the sheath, electrode 7 any further. Means are also provided to maintain the cloud of electrons within the tubular sheath 7 by providing electrostatic forces at the ends of this sheath. To this purpose, the casings 2 and 6 are connected by means of conductors 13 and 14 with potentials sufficiently be-

low the potential of cathode 8. Alternatively, special electrodes may be provided at the ends of sheath 7 to effect the same result.

Since the electrons of the cloud within the tube 7 cannot escape to any of the outer electrodes because of the magnetic and electrostatic forces, they can escape only by returning to the cathode 8. This, however, is a slow process for two reasons. First, the area of the cathode 8 is very small compared with the area of the boundary 12. Secondly, a returning electron can reach the cathode only if it approaches it at very nearly right angles, else its angular momentum will again carry it away from it. It is therefore seen that the electrons emitted by the cathode 8 are trapped in the region defined by the surface 12 and escape only after they have traversed it a multitude of times. It is therefore possible to trap inside the region 12 two very large equal and opposite electron currents, one flowing to the right and the other to the left, each being many times larger than the emission of the cathode 8. The axial currents cancel one another, while the rotary currents connected to the two streams have the same sign. This electron current rotating around the axis has a sign opposite to that of the current in the coil 5 which produces the magnetic field, that is, the rotating electron current tends to weaken the field near the axis. This has a beneficial effect from the point of view of the invention, as the magnetic field has a condensing lens effect and the new lens begins to act as a diverging lens only if the space charge effect outweighs the magnetic effect.

If the trapped electrons were allowed to accumulate in the enclosed space until their space charge repelled any further electrons emitted by cathode 8, a static cloud of electrons would be produced. Suitable electrodes, therefore, such as the electrode 16, may be used to remove the electrons at a certain desired rate, and by this to regulate the concentration of the space charge. The electrodes 16 preferably are kept at potentials only a little higher than the regular cathode potential to avoid undue heat development.

The effect of the lens system as described on the fast electrons used for microscopic image formation is illustrated in Fig. 2, which shows schematically the distribution of the magnetic field strength H and of the negative space charge density ρ along the axis. The portion 20 of this curve shows the magnetic field strength within the lens 1 and illustrates how this magnetic field is zero at the surface of revolution 11. The region 21 shows the negative space charge density within the tubular electrode 7.

In Fig. 3 there is shown the trajectory of a fast electron emitted from the primary cathode (not shown) and used for microscopic image formation, the distance r indicating the distance of the electron from the axis 4. The electron is bent toward the axis 4 by the condensing lens constituted by the magnetic coil 1 and away from this axis by the space charge lens comprising the cloud of electrons within electrode 7 until it becomes approximately parallel to the axis near the end of the space charge lens. The lens system illustrated in Fig. 1 combines to form a short focus lens which is a combination of the long magnetic lens 2 and the long diverging space charge lens. The focal length f of this lens is the projection on the axis 4 of the intersection of the initial tangent 22 and the final tangent 23 to the trajectory. It is therefore possible that this focal length can be made much smaller

than the longitudinal extension of the lenses and it can be reduced to almost any small value if the space charge lens is made sufficiently long. The focal length f is approximately an exponential function of this length of the space charge lens.

In Fig. 4, the upper portion of the figure illustrates the density distribution within the electrode 7 and shows the manner in which the region 12 contains a cloud of electrons surrounding the axis 4. The lower portion of Fig. 4 illustrates the space charge distribution ρ and the potential distribution ϕ in this region. The desired shape for the electron lens is achieved only by suitable injection of electrons. This shape, shown in Fig. 4, is obtained by shaping and positioning the auxiliary cathode 8 on the surface of zero field strength and by suitably regulating the injection of the electrons. The electrons accumulate in the tubular space 12 until they have depressed the potential of the axis 4 to the potential of the cathode 8. Beyond this point, no more electrons can reach the axis. In order to prevent the beam from hollowing out and reaching a static condition, the electrons must be removed at a sufficient rate by means of the electrodes 16.

From the foregoing description of the invention, it may be seen that the electron lens illustrated and described may be constructed to have an extremely short focal length. Because of this extremely short focal length of the lens system, in an electron microscope using such a lens system, larger numerical apertures may be employed, the spherical aberration of such larger apertures being corrected by the space charge lens of the lens system. By thus permitting the use of larger apertures and providing lenses of shorter focal length, the invention permits the construction of electron microscopes having a resolution limit which is less than any heretofore obtained.

Moreover, space charge lenses as described above may be used to achromatise an electron optical system, that is, to make the focal length independent of the electron velocity.

While only a particular embodiment of the invention has been shown, it will of course be understood that the invention is not limited thereto since various modifications may be made, and it is contemplated by the appended claims to cover any such modifications as fall within the true spirit and scope of the invention.

What I claim as new and desire to secure by Letters Patent of the United States is:

1. An electron lens for focusing an electron stream used for image formation comprising means for converging the electrons of said stream toward the axis thereof, means for establishing an auxiliary space charge along the axis of said stream, and means utilizing said space charge for diverging said electrons to a path substantially parallel with said axis.

2. In an electron microscope, a lens for focusing a stream of image-bearing electrons comprising magnetic means for converging the electrons of said stream, means for establishing an auxiliary space charge along the axis of said stream, and means utilizing said space charge for diverging said electrons to a path substantially parallel with said axis.

3. A space charge lens for focusing an electron stream comprising means for establishing an equipotential surface, magnetic means surrounding said equipotential surface, and means for in-

jecting an auxiliary stream of electrons within said equipotential surface to form a space charge therein for controlling said first stream.

4. A space charge lens for focusing an electron stream comprising means for establishing an equipotential surface, magnetic means for surrounding said equipotential surface, means to produce an auxiliary cloud of electrons confined within said equipotential surface, and means to remove electrons from said cloud.

5. In an electron microscope, a lens system for an electron beam used for image formation comprising a magnetic lens having a length along the axis of said beam greater than the diameter of said beam, and means for establishing a space charge lens in close proximity to said magnetic lens and having a length along said axis substantially equal to the length of said magnetic lens.

6. In combination, means for forming a primary beam of electrons, space charge lens means for focusing said beam of electrons comprising said tubular electrode surrounding said beam, cathode means to inject an auxiliary stream of electrons within said electrode, said electrode

20 being maintained at a positive potential with respect to said cathode means, magnetic means adjacent said electrode to produce rotation of electrons of said stream within said electrode, said magnetic means being of sufficient strength relative to the potential difference between said electrode and said cathode to prevent said electrons of said stream from reaching said electrode, and means to prevent the escape of electrons of said stream from the ends of said electrode.

7. In combination, means for forming a primary beam of electrons, space charge lens means for focusing said beam of electrons comprising a tubular electrode surrounding said beam, cathode means to produce an auxiliary cloud of electrons within said electrode, said electrode being maintained at a positive potential with respect to said cathode means, magnetic means adjacent said electrode to produce rotation of electrons of said cloud within said electrode, said magnetic means being of sufficient strength relative

30 to the potential difference between said electrode and said cathode to prevent said electrons of said cloud from reaching said electrode, means to prevent the escape of electrons of said cloud from the ends of said electrode, and means to remove electrons from said cloud to regulate the concentration of the space charge thereof.

8. The combination, in an electron microscope having a stream of electrons used for image formation, of an electron lens for focusing said stream comprising magnetic means for converging the electrons of said stream toward the axis thereof, a tubular electrode positioned in proximity to said magnetic means along the axis of said stream, means for producing an auxiliary cloud of electrons within said tubular electrode, said electrode being maintained at a potential positive with respect to said electron producing means, means for producing a magnetic field within said electrode to effect rotation of the electrons of said cloud, said magnetic field being of sufficient intensity to prevent electrons of said cloud from reaching said electrode, and means for preventing the electrons of said cloud from escaping from said electrode.

9. The combination in an electron microscope having a stream of electrons used for image formation, of an electron lens for focusing said stream comprising magnetic means for converging the electrons of said stream toward the axis

thereof, a tubular electrode positioned in proximity to said magnetic means along the axis of said stream, means located at a point of zero magnetic field between said magnetic means and said tubular electrode for producing an auxiliary cloud of electrons within said tubular electrode, said electrode being maintained at a potential positive with respect to said electron producing means, means for producing a magnetic field within said electrode to effect rotation of the electrons of said cloud, said magnetic field being of sufficient intensity to prevent electrons of said cloud from reaching said electrode, means for preventing the electrons of said cloud from escaping from said electrode, and means for removing electrons from said cloud to regulate the space charge thereof.
